UNITED STATES PATENT OFFICE.

DAVID HARNETT SHIPMAN, OF MERCED, CALIFORNIA.

WRENCH.

No. 863,108.

Specification of Letters Patent.

Patented Aug. 13, 1907.

Application filed March 23, 1907. Serial No. 364,155.

To all whom it may concern:

Be it known that I, DAVID HARNETT SHIPMAN, a citizen of the United States, residing at Merced, in the county of Merced and State of California, have invented certain new and useful Improvements in Wrenches, of which the following is a specification.

My invention relates to improvements in wrenches of the plier-type, especially designed for turning pipes or other like cylindric bodies, as well as being adapted for turning nuts and for cutting wire. Its objects are to promote facility and expedition of action and effectiveness in carrying out the aforesaid purposes, together with simplicity and economy of manufacture.

Said invention consists of certain features or instrumentalities substantially as hereinafter fully disclosed and specifically pointed out by the claims.

In the accompanying drawing illustrating the preferred embodiment of my invention—Figures 1 and 2 are opposite side views thereof. Fig. 3 is a cross-section produced through the jaws. Fig. 4 is a broken side view thereof, the jaws being spread apart or in open position.

In the disclosure of my invention, I employ two handle-equipped jaw-members 1, 2, the handles being designated as 3, 4, respectively, which jaw-members have their otherwise generally rectangular gripping surfaces or faces 5, 6 rounded out into concavities for a portion of their lengths as at 7, 8 as in adapting the same for more effectively engaging a pipe-section or other body of like outline when it may be desired to turn the same. It is also apparent that the jaw-faces are equally effective for receiving between them a nut, for turning it as in unscrewing it off a bolt or screwing it thereon, as well understood. One jaw-member 2, has its handle 4 integral therewith; and in diagonally opposite surfaces of the two jaws are longitudinal guide-grooves 9, 10 which, however, open out only laterally and not at their ends, or rather but partially at their inner ends, to limit the relative movement of said jaws and prevent the disengagement of the moving parts guided thereby, as will more fully be presently disclosed. The other jaw-member 1, has its handle 3 pivotally connected thereto at its extreme inner end some distance inward from the outer end of said handle as at 11, while said end of said handle crosses over toward, and stands laterally of the opposite jaw-member 2 for actuating the last-noted as later described. Said handle 3 has, a short distance inward from its jaw-actuating end, an oblique corner edge 12 beveled off to co-act with an opposite correspondingly shaped and beveled off edge 13 of the jaw-member 1 to serve as a wire-cutter.

A link 14, toggle-lever like in action, is pivotally connected as at 15, at its inner end to the handle of the jaw-member 2, a short distance inward from the latter.

Said link is also pivotally connected as at 16, in a suitable manner, to the handle of the jaw-member 1 near its outer end. Said link and an outer-end extension 17 of the handle 3 of the jaw-member 1, have their respective outer ends curved edgewise in opposite directions and provided at their outer ends with lateral studs or projections 18, 19, respectively, effective for engaging the guide grooves 9, 10 of the two jaw-members for directly actuating the latter as the handles of said jaw-members are requisitely manipulated. Said lateral studs 18, 19 travel in the grooves 9, 10 of the jaw-members along longitudinal lines, while the laterally edgewise curved portions of the lever 3 and of the link 11 describe arcs in their movement, which have the effect to move said jaw-members in relatively parallel lines, for effective gripping action, as will be readily appreciated.

This device is extremely simple, inexpensive of manufacture and effective in action.

75

I claim—

1. A wrench comprising handle-equipped jaw-members having longitudinal grooves in their diagonally opposite sides, one jaw-member being integral with its handle and the other jaw-member being pivoted to its handle, and a link pivoted at one end to the handle integral with its jaw-member, a short distance inward from said jaw-member, said link also being pivoted intermediate of its ends to the outer end of the jaw-member pivoted handle, said link and said pivoted jaw-member handle having their outer ends provided with integral studs engaging said grooves.

2. A wrench comprising handle-equipped jaw-members having longitudinal grooves in their diagonally opposite sides, one jaw-member being integral with its handle and the other jaw-member being pivoted to its handle, and a link pivoted at one end to the handle integral with its jaw-member, a short distance inward from said jaw-member, said link also being pivoted intermediate of its ends to the outer end of the jaw-member pivoted handle, said link and said pivoted jaw-member handle having their outer ends provided with integral studs engaging said grooves, also one of said jaw-members and one handle being adapted to serve as a wire-cutter.

3. A wrench comprising handle-equipped jaw-members having longitudinal grooves in their diagonally opposite sides, one jaw-member being integral with its handle and the other jaw-member being pivoted to its handle, and a link pivoted at one end to the handle integral with its jaw-member, a short distance inward from said jaw-member, said link also being pivoted intermediate of its ends to the outer end of the jaw-member pivoted handle, said link and said pivoted jaw-member handle having their outer ends provided with integral studs engaging said grooves, also said link and said jaw-member pivoted handle being curved at their stud-equipped portions toward each other.

In testimony whereof I affix my signature, in presence of two witnesses.

DAVID HARNETT SHIPMAN.
